SNOWPLOW

Filed May 6, 1932

FIG. 1.

FIG. 2.

FIG. 3.

FIG. 4.

UNITED STATES PATENT OFFICE

CARL H. FRINK, OF CLAYTON, NEW YORK

SNOWPLOW

Application filed May 6, 1932. Serial No. 609,679.

This invention relates to snow plows of the class set forth in my Patents No. 1,589,748 dated June 22nd, 1926 and No. 1,794,070 dated February 24th, 1931, and in 5 my pending application Serial No. 489,983 filed October 20th, 1930 in which the plow and its supporting frame are adapted to be mounted upon or attached to the front end of the chassis frame of a motor truck to be 10 propelled thereby ahead of the truck.

These plows are preferably provided with rearwardly diverging moldboards arranged at equal angles to and at opposite sides of the longitudinal center of the truck for 15 placing the snow to opposite sides of the roadway as the machine is propelled forwardly at greater or less speed, depending upon the depth and other conditions of the snow.

20 These machines are found to be highly efficient in the expeditious and economical removal of snow under practically all conditions, but obviously may be operated with greater speed in the removal of light snow even though the latter may be of considerable depth but when driven at high speed the snow is liable to be driven over the top of the moldboards and against the windshield and other parts of the machine at the 25 rear of the plow unless some provision is made for preventing this objectionable result.

Furthermore, it is well known that in 30 many instances, particularly when the plow is propelled forwardly at a relatively high speed, the snow displaced thereby will be piled up in drifts along opposite sides of the roadbed so that subsequent snow storms or 35 winds, transversely of the drifts formed by the snow plows, results in the formation of additional drifts or accumulations of snow in the previously plowed roadbed due to the 40 reduced wind velocity at the leeward side of the drifts formed by the snow plows.

The main object, therefore, of the present invention is to provide the upper edges of the moldboards with extensions or deflector plates which may be adjusted to project forwardly or rearwardly from the up-

per edges of their respective moldboards according to the condition of the snow.

For example, if the snow is relatively light, even though of considerable depth, the deflector plates may be adjusted to project 55 forwardly from the upper edges of the respective moldboards to partially overhang the same so that when the machine is driven forwardly at a correspondingly higher speed, the resultant upward thrust of the 60 snow across the moldboard will be limited by the deflector plates which will then serve to further deflect the snow laterally and outwardly considerable distances to the outside of the roadbed and over correspondingly 65 large areas, thereby obviating the formation of drifts along opposite sides of the roadway, and incidentally reducing the liability of formation of drifts in the previously plowed roadway.

On the other hand, if the snow is of excessive depth or weight requiring a corresponding reduction in the speed of operation of the truck, the deflecting plates may be adjusted to project rearwardly from the 70 upper edges of the respective moldboards, thereby reducing the resistance to the upward and lateral thrust of the snow, and permitting the plow to function in the usual manner.

Another object is to provide means for rigidly holding the deflector plates in their operative positions and also to permit the plates to be easily and quickly adjusted to 75 their inoperative or rearwardly projecting positions without disconnecting them from the moldboards or supporting frame.

A further object is to make the deflector plates of gradually increasing widths from 80 their inner ends toward their outer ends so that when adjusted to their operative positions, the outer ends will be considerably wider than their inner ends to assure the deflection of the snow over a wide area at 85 the outer sides of the roadbed.

Other objects and uses relating to specific parts of the device will be brought out in the following description.

In the drawing:

Figure 1 is a front end view of a snow 100

plow equipped with my improved deflector plates in their inoperative positions.

Figure 2 is a side elevation of the same plow showing one of the deflector plates in its operative position.

Figure 3 is an enlarged detail vertical sectional view taken on line 3-3, Figure 1, showing the deflector plate in its operative position and the toggle connections between said plate and the supporting frame for the moldboard.

Figure 4 is a horizontal sectional view, partly in top plan, taken along the line 4-4, Figure 3, portions of the moldboard, deflector plate and frame being broken away.

As illustrated, the snow plow comprises a pair of similar rearwardly diverging moldboards —1— mounted upon a suitable supporting frame —2— so as to extend rearwardly at equal angles to the longitudinal center of the machine, the frame —2— being adapted to be mounted upon or attached to the front end of a motor truck, not shown, but in a manner somewhat similar to that shown in my patents and pending application referred to.

The moldboards —1— are concavo-convex in cross section and are arranged with their concave sides facing forwardly, the lower edges of the moldboards being provided with scraper blades —3— adapted to travel along and in close proximity to the road surface.

The upper edges of the moldboards are returned inwardly and downwardly to form angular reinforcing flanges —4— which serve the double purpose of stiffening the moldboards and also for supporting a pair of similar but reversely arranged deflector plates —5—, one for each moldboard, the moldboards and deflector plates being preferably made of heavy sheet steel or equivalent material capable of withstanding the strains to which they are subjected.

These deflector plates —5— are of approximately the same length as the upper edges of their respective moldboards and are tapered from end to end and arranged with their wider ends outermost, the opposite longitudinal edges of each deflector plate being provided with lengthwise reinforcing flanges —6— and —7— projecting upwardly and rearwardly therefrom, the inner or lower flanges —6— being somewhat wider than the opposite flanges —7— and correspond approximately to the widths and lengths of the adjacent flanges —4— to which they are attached.

That is, the inner edge of the flange —6— of each plate is hinged at —8— to the inner edge of the adjacent flange —4—, as shown more clearly in Figures 3 and 4, so that when the deflector plate is adjusted for use its inner flange —6— will rest flatwise against and upon the upper face of the adjacent flange —4—, as shown in Figure 3,

the sections of the hinges being spot-welded or otherwise secured respectively to the flanges —4— and —6—.

The upper portions of the moldboards —1— are deflected forwardly at a considerable angle from a vertical while the major portions of the flanges —4— are disposed at approximately right angles to the adjacent portions of the moldboards.

The flanges —6— of the deflector plates —5— are disposed at obtuse angles to the major portions of the plates so that when the latter are adjusted for use they will project forwardly from the upper edges of their respective moldboards at acute angles to horizontal planes, thereby serving as continuations of the moldboards for limiting the upward thrust of the snow from the moldboards and deflecting the same laterally and outwardly beyond the roadbed aided by the gradually increasing widths of the blades from the inner to their outer ends.

Each of the deflector plates —5— is provided with an upwardly and inwardly projecting bracket —9—, spot welded or otherwise rigidly secured to the upper face thereof between the flanges —6— and —7—, when adjusted for use.

A toggle member —10— is pivoted at one end at —11— to the upper inner end of the bracket —9— and has its other end pivoted at —12— to a companion toggle member —13— which, in turn, is pivoted at —14— to a bracket —15— on the frame —2— some distance to the rear of the upper edge of the moldboard —1—, as shown more clearly in Figures 3 and 4.

The toggle member —13— extends some distance beyond the pivot —12— toward the bracket —9— in overlapping relation to the adjacent end of the toggle member —10—, said extension being provided with an aperture or apertures adapted to register with a similar aperture in the link —10— when the toggle is straightened for receiving a locking pin —16— by which the toggle members —10— and —13— may be firmly held in their straightened position for holding the corresponding deflector plate —5— in its operative position.

The locking pin —16— is attached to the member —10— by a flexible connection or chain —17— and is held against accidental displacement by a cotter pin —18—, the connection —17— serving to support the locking pin when withdrawn from the toggle members as shown by dotted lines in Figure 3, and having its other end secured at —17'— by spot-welding or other means to the toggle member —10—, Figure 3.

It will be noted upon reference to Figures 3 and 4 that the pivotal connection —12— between the toggle members —10— and —13— is located approximately midway between the pivots —11— and —14—, while

the locking pin —16— is located substantially midway between the pivots —11— and —12— so that when the locking pin is removed the toggle members —10— and 5 —13— may be flexed upwardly at the joint, thus permitting the deflector plate —5— to be rocked upwardly and inwardly about its pivot —8— and to the position shown by dotted lines in Figure 3.

10 The toggle member —13— preferably consists of two parallel links which are spaced apart transversely to receive the adjacent portion of the member —10— and are connected across the top by a cross bar —13'— 15 rigidly secured thereto by electric welding or otherwise substantially midway between the bolts —12— and —16— to form a stop for engaging the upper edge of the adjacent portion of the member —10— and thereby 20 limiting the downward flexing movement of the toggle to a substantially straightened position and incidentally alining the apertures for the locking bolt —16— to permit the latter to be easily inserted and removed. 25 Each of the brackets —15— is secured by bolts —15'— or equivalent fastening means to the frame —2— to form a part thereof for supporting the adjacent end of the toggle member —13—.

30 Operation

When the deflector plates —5— are adjusted for use, the flanges —6— will be brought into engagement with the adjacent 35 flanges —4— of the moldboards —1—, said flanges forming cooperative stops for limiting the forwardly swinging movement of the respective deflector plates at which time the corresponding toggle members —10— and 40 —13— will have been straightened whereupon the locking pins —16— will be inserted in their registering openings in the members —10— and —13— for locking the corresponding deflector plates in their operative 45 positions, it being understood that the toggles then form rigid brace connections between the brackets —9— and —15—.

These deflector plates are preferably adjusted to project outwardly from the upper 50 edges of their respective moldboards and locked in those positions when it is desired to propel the plow under relatively high speed, as for example, in the removal of light snow, in which case the deflector 55 plates form continuations of the moldboards and serve to deflect the snow from the upper portions of the moldboards laterally with an accelerated motion sufficient to distribute the snow more or less evenly to opposite 60 sides of the roadbed and at the same time to prevent the passage of the snow over the tops of the moldboards onto the windshield and other portions of the vehicle.

When the plow is being used to clear the 65 roadbed of heavier snow, it will, of course,

be propelled at a slower rate of speed without liability of passage of the snow over the tops of the moldboards in which case it would be advantageous to fold the deflector plates —5— inwardly beyond the upper 70 edges of the moldboards, as shown in Figure 1 and by dotted lines in Figure 3, to allow free upward and lateral passage of the snow along the moldboards without liability of packing against the undersides of the deflector plates. 75

When it is desired to fold the deflector plates —5— inwardly, it is simply necessary to remove the locking pin —16— and then to flex the toggle arms upwardly by hand or otherwise, aided by upward and inward pressure upon the deflector blades until the flanges —7— of said plates are brought into engagement with the outer edges of the then folded toggle members 80 —10—, as shown by dotted lines in Figure 3, at which time the deflector plates will be adjusted wholly to the inside of the upper edges of the respective moldboards with the brackets —9— extending downwardly 85 therefrom, as shown by dotted lines in Figure 3, it being understood that the weight of the plates against the toggle members —10— assist in holding the plates in their inoperative positions, owing to the fact that they will then be wholly at the inside of their respective pivots —8—.

It will be noted that one of the links as —13— of each toggle is composed of two members arranged in parallel spaced relation for receiving between them the adjacent end of the link —10—, the object of which is to give greater strength to the toggle and less shearing resistance upon the locking pin —16— and pivotal bolts 90 —12— and —14—.

Each of the deflector plates —5— is preferably supported upon the upper edge of its corresponding moldboard by a plurality of, in this instance three, hinges —8—, 95 suitably spaced lengthwise of the plate to afford ample support for said plate when adjusted for use.

It is evident, however, that other means may be provided for attaching the deflector plates to the moldboards in such manner as to permit said plates to be moved to and from their operative positions without disconnecting them from the moldboards and that other changes may be made in the 100 detail construction of the various parts of the plow and deflector plates without departing from the spirit of the invention.

What I claim is:

1. In a snow plow, a moldboard and a 105 supporting frame therefore, in combination with a deflector plate hinged to the upper edge of the moldboard to swing forwardly and rearwardly relatively thereto, and means for holding said plate in its for- 110

wardly projecting position, the moldboard and plate being provided with cooperative stops for limiting the forward movement of the plate.

5. 2. In a snow plow, a moldboard and a supporting frame therefor, in combination with a deflector plate hinged to the upper edge of the moldboard to swing forwardly and rearwardly relatively thereto, and toggle connections between the frame and plate adapted to straighten when the plate is moved forwardly for holding said plate in its forwardly projecting position.
10. 3. In a snow plow, a moldboard and a supporting frame therefor, in combination with a deflector plate hinged to the upper edge of the moldboard to swing forwardly and rearwardly relatively thereto, and toggle connections between the frame and plate adapted to straighten when the plate is moved forwardly for holding said plate in its forwardly projecting position, and means for locking the toggle in its straightened position to prevent flexing thereof.
15. 4. In a snow plow, a moldboard and a supporting frame therefor, in combination with a deflector plate hinged to the upper edge of the moldboard to swing forwardly and rearwardly relatively thereto, and toggle connections between the frame and plate adapted to straighten when the plate is moved forwardly for holding said plate in its forwardly projecting position, said plate having its free edge adapted to abut
20. 30. 35. against one of the toggle members when moved to its rearwardly projecting position for limiting said movement.
25. 5. A snow plow comprising a frame, rearwardly diverging moldboards mounted on the frame, plates hinged to the upper edges of the moldboards to swing forwardly and rearwardly therefrom, and toggle connections between each plate and frame adapted to straighten when the plate is
30. 40. 45. rocked forwardly for holding said plate in its adjusted position.
35. 6. A snow plow comprising a frame, rearwardly diverging moldboards mounted on the frame, plates hinged to the upper edges of the moldboards to swing forwardly and rearwardly therefrom, and toggle connections between each plate and frame adapted to straighten when the plate is rocked forwardly for holding said plate in
40. 45. 50. 55. its adjusted position, each toggle having releasable means for locking it in its straightened position.

In witness whereof I have hereunto set my hand this 27th day of April 1932.

CARL H. FRINK.
